COMBINED CIGARETTE BOX, CIGARETTE HOLDER, AND SMOKING DEVICE

Ernest R. Wilkinson, Santa Ana, Calif.

Application February 23, 1951, Serial No. 14,313

Term of patent 7 years

(Cl. D85—2)

To all whom it may concern:

Be it known that I, Ernest R. Wilkinson, a citizen of the United States of America, residing at Santa Ana, in the county of Orange and State of California, have invented a new, original, and ornamental Design for a Combined Cigarette Box, Cigarette Holder, and Smoking Device, of which the following is a specification, reference being had to the accompanying drawing, forming part thereof.

Figure 1 is a front perspective view of a combined cigarette box, cigarette holder, and smoking device, showing my new design, and

I claim:

The ornamental design for a combined cigarette box, cigarette holder, and smoking device, as shown.

ERNEST R. WILKINSON.
